UNITED STATES PATENT OFFICE.

HUGO HOHENSTEIN, OF NEW YORK, N. Y.

DESIGN FOR A CANDLE-SHADE.

SPECIFICATION forming part of Design No. 29,756, dated December 6, 1898.

Application filed November 10, 1898. Serial No. 696,084. Term of patent 3½ years.

To all whom it may concern:

Be it known that I, HUGO HOHENSTEIN, a citizen of the United States, residing at New York, in the borough of Manhattan, State of New York, have invented and produced a new and original Design for Candle-Shades, of which the following is a specification, reference being had to the accompanying drawings, forming part thereof.

- 10 o Figure 1 is a perspective view, and Fig. 2 is a vertical central section, of my new design.

As shown in the drawings, the leading or material feature of my design consists of an upper series of leaves A, a lower series of 15 larger depending leaves B, and a bunch of filaments C, hanging down over each leaf B.

The leaves A project upwardly above the shade-body D and the larger leaves B project downwardly below the rim of the shade.

The filaments C represent stamens terminated by anthers C', while the center pieces a represent pistils, so that the foliage has a flowery appearance imparted thereto. The bunches of filaments C hang down along the longitudinal centers or main veins of the 25 lower leaves.

What I claim as new is—

The design for a candle-shade, as herein shown and described.

In testimony that I claim the foregoing as 30 my invention I have signed my name in presence of two subscribing witnesses.

HUGO HOHENSTEIN.

Witnesses:

PAUL GOEPEL,
M. HENRY WURTZEL.
